UNITED STATES PATENT OFFICE

HENRY T. PAISTE, OF PHILADELPHIA, PENNSYLVANIA.

MULTIPLE-CIRCUIT PANEL.

No. 842,110.

Specification of Letters Patent.

Patented Jan. 22, 1907.

Application filed April 12, 1906. Serial No. 311,287.

To all whom it may concern:

Be it known that I, HENRY T. PAISTE, a citizen of the United States, residing in Philadelphia, Pennsylvania, have invented certain Improvements in Multiple-Circuit Panels, of which the following is a specification.

My invention consists in certain improvements in that class of electrical fixtures particularly designed to provide means for connecting and supporting electrical conductors and, if desired, fuse-plug sockets at the points where feeders having two or more conductors divide into a number of branch circuits each having the same number of conductors.

One object of my invention is to provide a distributing-panel of the above-noted type, which while consisting of any desired number of sections shall occupy less space than has hitherto been considered possible in similar constructions of the same capacity and which shall at the same time have its parts arranged in such manner as will best tend toward safety in operation and economy of material. These objects I attain as herein-after set forth, reference being had to the accompanying drawings, in which—

Figures 1 and 2 are respectively top and bottom plans of one form of my invention, the panel therein illustrated being particularly designed for use on a two-wire circuit. Fig. 3 is a side elevation of the panel shown in Figs. 1 and 2. Figs. 4 and 5 are vertical sections taken on the lines 4-4 and 5-5, respectively, of Fig. 1. Figs. 6 and 7 are respectively top and bottom plans of a form of multiple-circuit panel particularly designed for use on a three-wire circuit. Figs. 8 and 9 are plans of multiple-circuit panels, showing modifications of my invention and respectively designed for use on two and three wire circuits; and Figs. 10 and 11 are inverted or bottom plans of the structures shown in Figs. 8 and 9, respectively.

Referring to Figs. 1 to 5, inclusive, of the above drawings, A and A' are bodies of insulating material, such as porcelain, and upon the upper face of the first of these is carried a double-pole switch B, whose blades are designed to connect the terminals b and b' for the attachment of supply-feeders to other terminals b² and b³, respectively, all four of these terminals being held in position on the insulating-block A by screws, as shown in Figs. 2 and 4, which extend through the same. Both of the blocks A and A' are pro-

vided with relatively deep elongated recesses c and c', extending in two continuous lines, and also have connecting with them branch recesses c² and c³, respectively, extending substantially at right angles to and between the same in the under sides of said insulating-blocks.

Formed in the upper surface of both of the blocks A and A' are a number of circular recesses each surrounded by a raised annular collar d² and arranged in sets of two, each staggered relatively to the other. From each of the circular recesses a relatively straight channel or recess extends to the adjacent side of the panel, and in each circular recess are fixed metallic terminals d and d' for engagement with a fuse or cut-out plug, the first of said terminals consisting of a screw or bolt having in the present instance a hexagonal head and extending through to the bottom or under side of the block. The second terminal consists of the well-known threaded metallic ring or sleeve, and to this is electrically connected a laterally-extended metallic piece d³, which in each case extends into the straight recess connected to the corresponding fuse-plug recess. Each piece d³ has at its upper end a pair of lugs d⁴, bent upwardly and having midway between them a screw d⁵, with a washer, for the attachment of a branch electrical conductor.

On reference to Fig. 2 it will be seen that the recesses formed in the under surface of the two blocks A and A' are in two independent sets, and in these are placed metallic strips e, e', f, and f', of which the first two extend in the branch and main recesses c and c², respectively, while the last two extend in the branch and main recesses c' and c³, respectively. The screws d, forming one of the terminals of each of the fuse-plug sockets, extend into the various recesses in the under side of the blocks and form electrical connection with, as well as connect together, the various strips engaged by them.

One each of the strips e and f extends in the recesses c and c', formed partly in the block A and partly in the block A', so that they serve to rigidly connect or hold together said blocks, it being noted that one of the strips has an elongated hole in one of its ends for the reception of a screw d, so that the expansion and contraction of the material of the blocks and strips is permitted without danger of cracking or breaking the former.

With the above arrangement of parts the

terminal b is connected through one of the blades of switch B to the terminal b^2 and thence through the strips f and f' to the center terminals d of four fuse-plug sockets, 5 while the second terminal b' is similarly connected through its switch-blade terminal b^3 and the strips e and e' to the center terminals of four other fuse-plug sockets. In each case the threaded sleeves of the fuse-plug sockets 10 are connected to the branch terminal pieces d^3 . Moreover, the arrangement of parts is such that said terminal pieces d^3 along each side of the panel are alternately of different polarity, so that any pair of feeders for a 15 given branch circuit come off from the panel adjacent to each other.

It is of course evident that any desired additional number of blocks A' , with their sockets and connections, may be added in 20 continuation of the two blocks illustrated; but since these are mere duplications of said block A' with similar recesses and parts, I have illustrated the main block A with but a single auxiliary.

25 After the parts of the panel have been assembled fused insulating material is poured into the recesses c and c' in the under side of said panel, so as to fill them flush with the bottom surface thereof, and in order to prevent escape of this material from the open ends of the two channels in the last block A', I form these, as shown in Figs. 2, 4, 10, and 11, with transverse sockets c^3 , extending into the sides and bottom parts thereof for the 30 reception of pieces, usually of cardboard. Such pieces when in place extend across the ends of the recesses c and c' and are of a height sufficient to prevent escape of the insulating compound, which hardens upon cooling.

It will be seen that with the arrangement of parts described and illustrated the fuse-plug sockets are staggered relatively to each other, and thus make it possible to place a 45 given number of sockets on a block or blocks of less over-all dimensions than would otherwise be the case. Again, it will be seen that by placing the main connecting-bars e and f with their branches in recesses formed in the 50 under sides of the insulating-blocks the number of exposed conductors is reduced to a minimum, since when the various fuse-plugs are in place in their sockets only the switch-blades with their terminals and the 55 various branch terminals are exposed. To prevent possible short circuits between the switch-blades, I place between and parallel with them an upwardly-projecting arc shield c^6 , preferably formed, as in the present instance, integral with the body of the block A.

In Figs. 6 and 7 I have shown my invention as adapted for use in connection with a multiple-circuit panel on a three-wire system, the switch in this instance having three 65 blades and the insulating-blocks A^2 and A^3

having in their under face three independent recesses c , c' , and c^7 . In the first two of these are flat metallic strips or bars e and f , respectively connected to the two outside blades of the switch B' and engaged by the 70 center terminals d of the two outer fuse-plug sockets, respectively adjacent to the two sides of the panel. The recess or channel c^7 is intermediate the other two recesses and is of a zigzag form for the accommodation of 75 metallic strips f^3 and f' , connected to the center terminal of the switch B' and held in position by as well as electrically connected to the center terminal d of the four inner fuse-plug sockets of the panel. This center 80 or inner conductor is connected through a blade of switch B' to the neutral wire of the circuit, and with the arrangement of fuse-plugs illustrated the two terminals of each branch circuit are connected to the multiple-circuit panel in pairs, while the fuse-plug sockets each have, as previously described, a terminal for the connection of a feed-wire 85 and are arranged in pairs along the sides of said panel. As before, it will be noted that 90 the fuse-plug sockets are staggered relatively to each other, so as to economize space to a maximum extent and permit the use of a relatively small panel for the accommodation of a given number of sockets and branch 95 circuits.

Other applications of my invention are shown in Figs. 8 to 11, inclusive, the arrangement being such that the switches are placed on the branch-circuit sides of the fuse-plugs 100 instead of on the feeder sides, as in the construction shown in Figs. 1 to 4, inclusive. In any case, however, the bars or strips serve to hold together the various sections or blocks constituting the various parts of the panel 105 and are carried in channels or recesses formed independently of each other in the under surface of said blocks, while the fuse-plug sockets are staggered relatively to each other in order not only to reduce the amount of material required, but also to lessen the over-all 110 dimensions of the panel.

In the form of multiple-circuit panel shown in Figs. 8 and 10 the terminals D and D' are provided for the attachment of feeders from a source of current-supply. These are carried on a section or block A^4 of insulating material, mechanically connected to the second section A^5 by means of metallic strips or connections, as shown, which extend in recesses or channels formed in the opposite face of said sections. As before, the section A^4 , which may be indefinitely duplicated, is provided with a plurality of fuse-plug sockets, one terminal of each of which is connected to one or the other of the metallic strips e or f , attached to the feeder-terminals D and D'. On each side of the section A^5 is provided a switch B', and each of these switches has one pair of its terminals 125 130

connected to two of the metallic shells of a pair of fuse-plug sockets, these sockets, as before, being staggered relatively to each other and of opposite polarity. The other 5 terminals of the switches are placed at the sides of the panel for the reception of branch-circuit conductors.

In the case of the construction shown in Figs. 9 and 11, which has been adopted for 10 use on a three-wire circuit, two of the fuse-plug sockets have their central terminals connected to a neutral terminal D^2 by means of strips f^3 and f^4 , while the two remaining plugs have their central terminals respectively connected to the positive and negative 15 feeder-terminals D and D' through strips e and f .

As in the case of the panels shown in Figs. 5 and 7, switches B^2 are interposed between 20 the fuse-plug sockets and suitable terminals for attachment of branch-circuit conductors.

I claim as my invention—

1. A multiple-circuit panel consisting of a plurality of sections of insulating material, a 25 plurality of metallic connections all on one face of said panel, and a plurality of fuse-plug sockets on the other face thereof, each socket having one terminal engaging one of said metallic connections and the other terminal formed for the attachment of a conductor, said metallic connections serving to hold together the sections of the panel, substantially as described.

2. A multiple-circuit panel consisting of a 35 plurality of sections of insulating material, a plurality of metallic connections and a plurality of fuse-plug sockets, each socket having one terminal engaging one of said metallic connections and a second terminal for the attachment of a conductor, and said sockets being staggered relatively to each other, substantially as described.

3. A multiple-circuit panel consisting of a 45 plurality of sections of insulating material, a plurality of metallic connections on one face of said panel and a plurality of fuse-plug sockets on the other face thereof, each socket having one terminal engaging one of said metallic connections and a second terminal for 50 the attachment of a conductor, said metallic connections serving to hold together the sections of the panel, and said sockets being staggered relatively to each other, substantially as described.

55 4. A multiple-circuit panel consisting of a plurality of sections of insulating material, a plurality of metallic connections on one face of said panel and a plurality of fuse-plug sockets on the other face thereof, each socket having one terminal engaging one of said metallic connections and a second terminal for 60 the attachment of a conductor, said metallic connections serving to hold together the sections of the panel, and said sockets being staggered relatively to each other, with a

switch carried by one of said sections and connected in circuit with the socket-terminals, substantially as described.

5. A multiple-circuit panel consisting of a plurality of sections of insulating material, a 70 plurality of fuse-plug sockets on one face of the panel, each having a terminal for the attachment of a conductor, there being channels in the opposite face of the panel and metallic connections therein, said metallic connections being engaged by the second terminals of the fuse-plug sockets and serving to hold together the sections of the panel, the terminals for the attachment of conductors being arranged to cause said conductors to extend from the panel in lines at right angles to the general lines of the metallic connections thereof, substantially as described.

6. A multiple-circuit panel consisting of a 75 plurality of sections of insulating material, a series of fuse-plug sockets on one face of said panel, a plurality of series of metallic strips extending on the opposite face of the panel, means for connecting each series to one 80 branch of a feeder-circuit, means for connecting one terminal of each fuse-plug socket to a conductor and the remaining terminal to one of said connections, said sockets being arranged in pairs attached to metallic connections of opposite polarity, the sockets being 85 staggered relatively to each other, substantially as described.

7. A multiple-circuit panel consisting of a 90 plurality of sections of insulating material, a plurality of substantially straight channels extending longitudinally of the panel, a series of lateral branches extending from each channel toward the other, a series of metallic strips in each channel, fuse-plug sockets on the face of the panel opposite that having 95 said channels, one terminal of each socket being connected through the insulating material of the panel to one of the metallic strips, the connections being arranged so that successive plugs along the sides of the 100 panel are of opposite polarity, substantially as described.

8. A multiple-circuit panel consisting of a 105 plurality of sections of insulating material, metallic conductors extending on one face of the panel, means for connecting said conductors to electroreceptive devices, and other means for connecting the various conductors to a source of current-supply, certain of the 110 conductors being slotted at their points of connection to permit of the expansion or contraction of the parts of the panel, substantially as described.

9. A multiple-circuit panel consisting of a 115 plurality of sections of insulating material, a series of fuse-plug sockets on one face of said panel, each having a terminal extending through the panel, a plurality of series of metallic strips extending on the opposite face of the panel having main and laterally-extend- 120

ing portions and serving to mechanically connect the sections of the panel, said strips being engaged and held together by the said terminals of the fuse-plug sockets, and each 5 of said sockets having a second terminal for the attachment of branch-circuit conductors, substantially as described.

10. A multiple circuit panel consisting of a plurality of sections of insulating material, a plurality of fuse-plug sockets on said sections each having one terminal for the attachment of a branch-circuit conductor extending substantially at right angles to the general line of the panel, said sockets being arranged in 15 pairs along the sides of the panel, a switch on one of the sections, a plurality of series of metallic conductors extending in the general line of the panel and all on the side thereof opposite that having the sockets, certain of 20 the second terminals of the fuse-plug sockets being connected to one of said series of con-

ductors and the remainder to the other series, substantially as described.

11. As a new article of manufacture, a section for a multiple-circuit panel consisting of 25 a block of insulating material having on one face a fuse-plug socket or sockets and provided with an open-ended recess or recesses formed in its other face, said recess or recesses being provided with transverse slots adjacent 30 to said open end or ends and containing conductors, with a piece in each set of said slots for closing the open end of each recess, substantially as described.

In testimony whereof I have signed my 35 name to this specification in the presence of two subscribing witnesses.

HENRY T. PAISTE.
